UNITED STATES PATENT OFFICE.

VINCENZO BENEDETTI, OF PALISADE, NEW JERSEY.

GAITER.

1,230,652.

Specification of Letters Patent. Patented June 19, 1917.

Application filed March 15, 1917. Serial No. 155,003.

To all whom it may concern:

Be it known that I, VINCENZO BENEDETTI, a citizen of the United States, and a resident of Palisade, in the county of Bergen 5 and State of New Jersey, have invented a new and Improved Gaiter, of which the following is a full, clear, and exact description.

Among the principal objects which the present invention has in view are: to provide a separate gaiter with means for drawing the edge sections thereof into close contact with the shoe; to provide a gaiter of the character mentioned for supporting the arch of the foot; and to provide a gaiter of 15 the character mentioned equipped in simulation of a permanently attached shoe top.

Drawings.

Figure 1 is a side view of a shoe and a 20 gaiter therefor constructed and arranged in accordance with the present invention;

Fig. 2 is a front view of the same;

Fig. 3 is a bottom view of the same;

Fig. 4 is a front view of a shoe and a 25 gaiter applied thereto, the gaiter being constructed in accordance with a modified form of the invention;

Fig. 5 is a side view of a shoe and a 30 gaiter therefor constructed and arranged in accordance with a further modified form of the invention;

Fig. 6 is a perspective view showing independently the gaiter shown in Fig. 5.

Description.

As seen in the drawings, the shoe 8 is constructed in the usual manner and is what is known as a low shoe. Over this is disposed in service a gaiter 9 constructed in accordance with the present invention. The 40 gaiter 9 may be constructed from any suitable material, such as the various kinds of leather used for this purpose, or the various fabrics which are sometimes employed. In

45 any event, the sides are shaped and stretched in form across the heel edge 10 and the foxing edge 11, to correspond with the shape of the shoe 8 over which they are drawn.

To effect these purposes, the arch ends 12 50 of the gaiter 9 are drawn over a last to obtain the required shape and the extremities thereof are permanently connected with a shank strap 13. The shank strap 13 is preferably shaped to correspond with the shank 55 of the shoe so that if the bottom of the shoe is exposed to view, the leather of the strap

13 carries out the illusion desired, to the effect that the gaiter 9 is a part of the permanent and unit structure of the shoe.

The gaiter 9 is provided with an entrance 60 opening. As shown in the drawings, the opening is closed by a tongue 14 in simulation of the tongue usually employed with what are known as laced shoes. The edges 15 of the entrance opening are drawn together by lacing 16. Where other forms of shoe-fastenings are desired, buttons and buttonholes may be used as substitutes for the shoe lacing and covering tongue above described. 70

It is obvious that when employing a gaiter 75 constructed and arranged in accordance with the present invention, the same may be drawn close to the foot to fit the same snugly, employing to this end the lacing 16 or other fastening substitute therefor. In all events, the strain on the material composing the gaiter 9, tends to seat the edges 10 and 11 firmly in their service relation to the shoe 8. 80

Where it is desired to obtain a closer fit of the gaiter 9 about the instep for supporting the shank of the shoe and the arch of the foot, this may be accomplished by the individual wearer drawing the fasteners 85 closer than usual.

It is obvious that when the gaiters 9 are to be installed in service relation to the shoe 8, the lacing 16, if such be the form of fastening, is opened until the forward portion of 90 the shoe can be inserted through the gaiter 9 above the shank strap 13 thereof. The gaiter is drawn back until the opening therein at the rear of the strap 13 may be slipped over the heel of the shoe and adjusted to 95 position upon the stiffening thereof. When the edges 10 and 11 have been properly adjusted the fastening devices are manipulated to draw close to the shoe and foot the gaiter 9 and the edges 10 and 11. 100

When constructed and arranged in accordance with the present invention, the edges 10 and 11 are held by the strain of the fastener in their approved service relation to the shoe 8, and unseemingly curve or separation of said edges from the body of the shoe is avoided. 105

In the modified form of the invention shown in Fig. 4 of the drawings, the lacing 16 is started above a series of straps 17. 110 The straps 17 are secured in service by buckles 18. A resilient connecting strap 19

is disposed at opposite sides of the opening of the gaiter 9 to hold the edges of the gaiter in juxtaposed relation while the lower fastener is secured. By this means the need 5 for holding the free edges of the gaiter together with one hand while the fastener is secured with the other, is avoided.

In Figs. 5 and 6 of the drawings the modification disclosed consists in providing a 10 low upper 20 shaped in correspondence with the upper of what is known as an Oxford tie. In conjunction with the lacing 16 used for closing said upper 20, is a strap 21, which is secured by the buckle 22. The 15 straps 21 and 17 are preferably formed as integral extensions of the body of the uppers 9 and 20.

It will be understood that in all forms whether that designated herein as the preferred form or those designated as modi- 20

fied forms, the fastening device whether it be the strap 17, buttons, or the lacing 16, shall be so shaped as to draw the shank strap 13 and arch ends 12 firmly under the arch of the foot.

25

Claim.

A gaiter having flexible sides molded to conform to the shoe and foot therein, said gaiter embodying arched ends shaped to conform with the shoe adjacent the shank 30 thereof; a shank member permanently secured to the terminal edges of said ends in correspondence with the shape of the shoe to which said gaiter is fitted; means for drawing the entrance edges of said gaiter 35 together; and an elastic connection extending between the entrance edges of the gaiter adjacent the lower edge of said gaiter.

VINCENZO BENEDETTI.
